UNITED STATES PATENT OFFICE.

JOHN H. STAUBLY, OF NEW YORK, N. Y.

BOOTJACK.

1,178,109.

Specification of Letters Patent.

Patented Apr. 4, 1916.

Application filed April 12, 1915. Serial No. 20,911.

To all whom it may concern:

Be it known that I, JOHN H. STAUBLY, a citizen of the United States, residing in the city, county, and State of New York, have invented a certain new and useful Improvement in Bootjacks, of which the following is a specification, reference being had to the accompanying drawings.

The object of this invention is to provide a novel and convenient mechanical device for removing foot wear, but more particularly for removing "rubbers" from shoes without having to touch said rubbers with one's hands, and without bending the body; my said improvement being specially valuable and desirable when removing wet or muddy rubbers.

My said boot jack is illustrated in the annexed drawings, in which—
20 Figures 1, 2 and 3 are side elevations of my improved jack, illustrating also the manner of using the same to remove a rubber from an ordinary shoe; Fig. 1 illustrating the shoe and rubber as about to be placed in proper position on the jack, to remove the rubber, Fig. 2 illustrating the rubber in such position, and Fig. 3 showing the jack holding the rubber while the shoe is being withdrawn from said rubber. Fig. 4 is a top 25 or plan view of the said jack and Fig. 5 is a relatively enlarged, perspective view of the slidable clamping member *d* which is specially provided to hold the heel portion of the rubber while the shoe is being withdrawn from said rubber, as seen in Fig. 3. In Fig. 6 I have shown the bottom or sole of a rubber in order to explain clearly a certain lip or projection by means of which I am able to hold the foot portion of the rubber 30 in place while the shoe is being drawn out of said rubber.

Referring to these drawings, the letter *a* indicates a rubber over-shoe of ordinary construction excepting that it has secured to the sole, preferably just forward of the so-called "hollow of the foot," a rearwardly projecting lip or plate *b* which may be riveted to the sole or may be inserted in said sole when the rubber is made. This lip *b* however, 45 forms no part of this present invention as I propose immediately filing a separate application for the patent for said rubber improvement.

My improved boot jack consists chiefly of 50 an elongated plate *c*, a heel-clamp *d* slidably

mounted on said plate and a stop-plate *e* fixedly mounted on the plate *c* just ahead of the said slidable heel clamp. The heel-clamp *d* is formed, as here shown, with an enlarged, offset, rear-end portion *d'* that is 60 located in a slot *c'* in plate *c* in such manner that the heel-clamp may slide longitudinally on plate *c* a limited distance and said plate *d* is held normally in position just at the rear of the fixed stop-plate *e* by a spring 65 *f* which is fastened at one of its ends to the plate *d'* and at its other end to the front end portion of the plate *c*. When it is desired to use my described jack the rubber is first placed on the stop-plate *c* (see Fig. 1) with 70 the heel portion located in front of a V-shaped notch *d*² in the heel plate and with the lip *b* just in front of the stop-plate *e*. The rubber is then moved rearward bodily, thus hooking the lip *b* under the stop-plate 75 *e* and, simultaneously forcing the heel portion of the rubber into the notch *d*² and pushing the heel-plate *d* rearwardly against the restraining force of the spring *f* which thus holds the notched heel-plate tightly against 80 the heel portion of the rubber (see Fig. 2) so that, when the shoe is drawn upward, the rubber is held from moving while the shoe is withdrawn from said rubber (see Fig. 3). So soon as the shoe is thus withdrawn, the spring *f* forces the rubber forward, and separates the lip *b* from the stop-plate *c*, and the rubber drops to the floor. 85

It will thus be seen that, by the use of a jack of my described construction and operation, wet or muddy rubbers may be readily removed from boots or shoes without bending the body of the wearer of such rubbers.

Having thus described my invention, I 95 claim as new and wish to secure by Letters Patent:

1. A device of the type described, including a longitudinally slotted base having a resiliently controlled stepped boot or shoe 100 heel engaging member, the initial or lower tread thereof being positioned to engage and slide under said base, the intermediate riser thereof being extended upwardly slightly forward through the slot of said 105 base, and the upper tread being forked or bifurcated and arranged to engage the heel, said base having secured thereto at its forward end, a stepped member, with its forward end arranged to engage the sole of the 110

boot or shoe, slightly forward of the heel or "hollow-of-the-foot" conforming portion of the sole.

2. A device of the type described for 5 moving overshoes or "rubbers," including an upraised longitudinally slotted base, said base being slightly upwardly and forwardly inclined, a stepped member with the initial or lower tread positioned to engage and slide 10 under said upraised base, the intermediate riser extending slightly upwardly and forwardly through the slot of said base, the up-

per tread being forked or bifurcated and arranged to engage the heel, said base having secured thereto at its forward end, a resilient member having connection with said base and said stepped member to cause the latter to forcibly engage the shoe-heel, a second stepped member secured to the base near its forward end to engage a lip upon 20 the shoe-sole, slightly forward of the heel.

JOHN H. STAUBLY.

Witness:

FRANK H. ALLEN.
